WOVEN WIRE FABRIC

Albert S. Knapp, Worcester, Mass., assignor to G. F. Wright Steel & Wire Co., Worcester, Mass., a corporation of Massachusetts

Application June 28, 1954, Serial No. 439,602

2 Claims. (Cl. 245—10)

This invention relates generally to woven wire fabrics, and more particularly to woven wire fabrics of coarse or open mesh type, such as hardware cloth, wire lath or netting and the like.

The flexible wire used for such coarse mesh fabrics is invariably much heavier in gauge than the wire used for fine mesh fabrics, such as screen cloth, wire gauze and the like. Because of this, it has never been practical, in the manufacture of these coarse mesh wire fabrics, to make use of certain weaving techniques which give to fine mesh wire fabrics the woven-in selvage edges, longitudinally of the web, which are characteristic of various woven textile products.

That is to say, the usual machines for producing fine mesh wire fabrics employ (in similar fashion to a textile weaving machine) a transversely reciprocating shuttle, the latter carrying in coiled or spooled form, a supply, in great length, of the fine gauge wire which provides the fine mesh fabric's continuous weft and which, at each shuttle reversal, is incorporated in a finished selvage, along both sides of the web. However, since such a weft supply shuttle can carry only a very limited length of the much heavier gauge wire used in coarse or open mesh fabrics, it is neither practical nor economical to produce coarse mesh fabrics in this fashion, because of need for frequent machine shutdowns to replenish the shuttle's weft supply.

Instead, it has long been common practice, in manufacturing these coarse mesh wire fabrics, to supply the weft, not in the above described continuous fashion from a reciprocating shuttle, but rather by a succession of individual relatively short wires which are projected one after another across the set of spaced parallel wires, always heretofore of uniform circular cross section, that provide the longitudinally advancing warp components of every such coarse mesh wire fabric. To give to a coarse mesh wire fabric made in this non-stop fashion, the required longitudinal selvage edges, it was the practice many years ago (see Scarles Patents Nos. 345,735 and 355,561) to interloop or twist together the projecting ends of the individual transverse weft wires; this provided the fabric, beyond each of its outermost warp wires, with a continuous selvage edge. But the latter, because of its thickness, was unduly resistant to the bending, flexing, rolling and the like, which every such fabric, in ordinary use, must undergo.

Selvage edges of these patented Scarles types, for coarse mesh wire fabrics, were rendered practically obsolete by the advent of spot welding, which made it very easy for each individual transverse weft wire (see Sommer Patent No. 1,783,948) to be rigidly connected with the fabric's two outermost warp wires, so that with subsequent cutoff of the weft wires' projecting ends, these outermost warp wires would serve as the longitudinal selvage edges of the fabric. But welded selvage edges as disclosed in the aforesaid Sommer patent are invariably crude and unsatisfactory from two standpoints, viz.: (1) because every cutoff weft wire always presents, just beyond its weld,

2

a sharp edge or burr, as a constant hazard to the hands and clothing of anyone working with the fabric, and (2) because each outermost warp wire, from pressure of the welding electrodes, is oftentimes subject to outward lateral deflection into the fixed plane of weft wire cutoff, with resulting severance or weakening of the so-welded selvage edge whenever such a deflection occurs.

Efforts made heretofore to obtain more satisfactory and reliable welded selvage edges for these coarse mesh wire fabrics have introduced expensive complications; see for example the fabric of Harter Patent No. 2,024,796, which requires that each individual transverse weft wire be extended beyond a "holding weld" to the fabric's outermost warp wire, to permit of its being bent over against and welded to the next adjacent (and similarly bent) transverse weft wire.

My invention, eschewing such and similar complications, has as its primary object the provision of welded selvage edges for coarse mesh wire fabrics, in the simple fashion of the aforesaid Sommer patent, but without the disadvantages (1) and (2) above of the Sommer construction.

Other and further objects and advantages of my invention will be apparent from the following detailed description thereof, taken in connection with the accompanying illustrative drawings in which

Fig. 1 is a plan view of the coarse mesh wire fabric of my invention, and showing schematically, from right to left, the successive steps involved in the formation of its novel welded selvage edges.

Fig. 2 is a corresponding schematic view in side elevation.

Fig. 3 is a fragmentary view, on a greatly enlarged scale, illustrating the favorable coplanar relation of the connected parts, along each welded selvage edge of my invention.

Fig. 4 is a large scale sectional view illustrating, by comparison with Fig. 3, the unfavorable edge conditions that are created by said Sommer patent's utilization, for welded selvage edge purposes, of the conventional outside longitudinal warp strand of a coarse mesh wire fabric.

Referring first to Figs. 1 and 2, the illustrated fabric is made by interweaving, in conventional manner, a succession of spaced transverse round wires 1, 1, with a set or series of similarly spaced longitudinally advancing warp wires; the latter, as here shown, include a plurality of the usual round wires 2, 2 preferably of the same gauge as the wires 1, 1, and also, along each side of the fabric, outwardly of said round warp wires 2, 2, a single flat wire 3 of thin strip form, whose substantially rectangular cross section has a relatively high width-to-thickness ratio.

Each flat warp wire 3 is disposed flatwise in the plane of the fabric, and each has a thickness which is no greater, in any case, than the diameter of the companion circular-section warp wires 2, 2; thus said two outside warp wires 3, 3 are not unduly resistant to the bending, flexing and rolling of the completed wire fabric, nor to the conventional weaving operation by which said fabric is formed.

In said weaving operation, these two outside warp wires 3, 3, advancing flatwise, preferably partake, along with the intermediate round warp wires 2, 2, of the usual repeated shed formations through which the successive filling or weft wires 1, 1 are projected, as by way of a suitable guide tube 4, Fig. 2. As a result of this conventional interweaving, the round weft wires 1, 1, upon emergence from the shed, have the usual alternate over and under crossed relation with said outside flat wires 3, 3, and have their ends projecting slightly beyond said outside flat wires 3, 3, as shown at 5, 5, Fig. 1.

The next operation, performed by suitably timed electrodes 6, 6 above and below the path of each flat wire 3,

is to produce a weld at each place where the successive filling wires 1, 1 cross each of the flat outside warp wires 3, 3 as indicated at 7, 7 on the drawings.

The final step in the manufacture of my improved wire fabric is to cut off the projecting ends 5, 5 of each so-welded round weft wire 1, 1, by the suitably timed operations of a pair of oscillatory cutters 8, 8, flanking the flat wires 3, 3, and each providing a blade 9 whose movement is, for all practical purposes, in the same vertical plane as that occupied by the thin outer face 10 (see Fig. 3) of the associated flat wire 3.

It is to be particularly noted, in the case of each flat outside warp wire 3, that the latter's inherent very high resistance to lateral deflection, in the plane of the fabric, from pressure of electrodes 6, 6, makes it practically impossible for said wire's outer face 10 to deviate in even the slightest degree from the aforesaid fixed vertical plane in which the associated cutter blade 9 is operative. Therefore, by the successive operations of the cutters 8, 8, the projecting ends 5, 5 of all of the weft wires 1, 1, are so sheared off, as to leave the latter, in every case, substantially flush (i. e. coplanar), as shown at 11, Figs. 1 and 3, with each flat wire's thin outside face 10. This gives along each side of the completed fabric a welded selvage edge construction which, because of the width of the flat wire 3, is desirably very resistant to lateral bending or sagging in the plane of the fabric. Furthermore, the outside surface (Fig. 3) of each welded selvage edge is uniformly smooth and continuous, and presents no sharp projections of a character that might cause injury to the hands of anyone working with the fabric.

Such would not be the case, were the so cut-off weft or filling wires 1, 1 welded to an outer longitudinal or warp wire 12 (Fig. 4) of the customary round cross section shown in the aforesaid Sommer patent. In that situation, every such cut-off weft wire 1, 1, along both side edges of the fabric would present, adjacent its weld, a sharp corner or edge 13, Fig. 4, as a constant hazard to the hands of anyone working with the fabric.

Furthermore, such a round outermost warp wire (see Fig. 4) has such low resistance to sidewise or horizontal deviation, that portions of same from pressure of the

welding electrodes, can be and are in practice very easily deflected into the fixed vertical plane path of the cut-off blades; in any such case a welded selvage edge of the Sommer construction shown by Fig. 4 would be partially severed, and the fabric as a whole materially weakened.

I claim:

1. An open mesh wire fabric of the class described, including a set of spaced parallel longitudinal warp wires of uniform circular cross section, a succession of spaced transverse filling or weft wires of similar cross section disposed in crossed relation to said warp wires and projecting at both ends therebeyond, and a pair of outermost flexible warp wires along each side of said set and also crossed by said weft wires, said two outermost warp wires being of flat strip form disposed flatwise in the fabric's plane, and of a thickness no greater than the diameter of said circular-section warp wires, with said weft wires spot welded at their points of crossing to said two outermost flat section warp wires and sheared off in coplanar relation with the latter's thin outside faces.

2. A open mesh wire fabric of the class described, including a set of spaced parallel longitudinal warp wires of uniform circular cross section, a succession of spaced transverse filling or weft wires interwoven in over-and-under relation with said warp wires and projecting at both ends therebeyond, and a pair of outermost flexible warp wires along each side of said set and also crossed by said weft wires, said two outermost warp wires being of flat strip form disposed flatwise in the fabric's plane, and of a thickness no greater than the diameter of said circular-section warp wires, with said weft wires spot welded at their points of crossing to said two outermost flat section warp wires and sheared off in coplanar relation with the latter's thin outside faces.
